UNITED STATES PATENT OFFICE

MALCOLM KENNETH DOUGLAS, OF NEW YORK, N. Y., ASSIGNOR TO AMERICAN RADIA-
TOR COMPANY, OF NEW YORK, N. Y., A CORPORATION OF NEW JERSEY

MOLDING APPARATUS

Application filed March 26, 1929. Serial No. 349,913.

My invention relates to new and useful improvements in molding apparatus, and more particularly to apparatus for forming the sand mold in a pipe flask.

5 An object of my invention is to provide an apparatus by which pipe flask sand mold may be made efficiently and accurately so that there will be a minimum of product loss from defective molds.

10 Another object is to provide an apparatus by which a plurality of molds may be made simultaneously.

The invention consists in the improved construction and combination of parts, and 15 their aggroupment in operative relation, to be more fully described hereinafter and the novelty of which will be particularly pointed out and distinctly claimed.

In the accompanying drawings, to be 20 taken as a part of this specification, I have fully and clearly illustrated a preferred embodiment of my invention, in which drawings—

Figure 1 is a view in front elevation of my 25 apparatus;

Fig. 2 is a view in side elevation looking from the left toward the right of Fig. 1 and showing the upper portion thereof with a lifter member applied thereto;

30 Fig. 3 is a top plan view of Fig. 2;

Fig. 4 is a top plan view of the flask shown in Fig. 1;

Fig. 5 is a bottom plan view of the flask;

35 Fig. 6 is a view in front elevation similar to Fig. 1, but showing the stripper plate in raised position;

Fig. 7 is a detail of a pattern bar in longitudinal central section;

Fig. 8 is a view in front elevation and 40 partly in section of a stripper plate;

Fig. 9 is a top plan view of the stripper plate shown in Fig. 8, and

45 Fig. 10 is a view in front elevation and partly in section showing a completed mold provided with a core and ready for pouring.

Referring to the drawings by characters of reference, the numeral 1 designates a flask body, preferably of cast-iron, comprising 50 a plurality of cylinders 2 which are

joined by webs 3. The cylinders 2 are hollow, each having a concentric cylindrical bore extending longitudinally therethrough to provide casting chambers 4 which are of a radius equal to the radius of the pipe plus the sand mold thickness. At the ends of the body and in the planes of the ends thereof, are transversely extending, surrounding flanges, that at the top end being designated 5 and that at the bottom end, which constitutes a base member, being designated 6. Extending between the flanges 5, 6 and along the cylinders 2 are reinforcing ribs 7 joined by transverse ribs 8 which surround the body 1. Extending downward from the flange 5 at the sides of the body 1, are block members 9 having downward facing hooks 10. Through the blocks 10 and the flange 5 are vertical guide openings or apertures 11. Through the flange 6 at the sides of the body 1 are apertures 12 for securing the body 1 to a supporting member. The top or upper ends of the chambers 4 are enlarged, as at 13, for a purpose to be described. The side walls of the cylinders 2 are perforated, as at 14, to vent the mold.

The flask body 1 is supported on a bottom plate or board 15 which is preferably mounted on the platform 16, of a vertically reciprocable jolt machine, by which the molding sand is rammed. The jolt machine, generally designated 16', may be of any well known type and is not part of my invention. Rigidly fixed to the platform 16 are pins 17 which project upward through the plate 15 and the apertures 12. Transversely through the pins 17 adjacent their upper ends are longitudinally extending slots 18 through which wedges 19 are driven to clamp the body 1 to the jolt machine. Concentric with the chambers 4 are apertures 20 in the plate 15, and in which are positioned bushings 21 having downward converging bores 22, each of which is concentric with its chamber 4.

Supported on the flask body 1 is a stripper plate 23 having spacer means or feet 24 which rest upon the top flange 5 adjacent the sides of the body 1 to maintain the plate 23 in spaced relation to the body 1. Concentric with the guide apertures 11 are guide aper-

tures 24' in the plate 23. Concentric with the chambers 4 are circular apertures 25 in plate 23, and depending from the plate 23 are sleeve members 26 which extend into the apertures 25 and are secured rigidly therein by screws 27, or the like. The bores of the sleeves converge downward for the major portion of their lengths, as at 28, and at their bottom ends are cylindrical, as at 29, and of a diameter equal to the diameter of the mold pattern bar to be described. At the ends of the plate 23 are hand-grips 30, preferably substantially U-shaped members, which are secured rigidly to the plate by bolts 31, or the like.

15 Positioned within each of the chambers 4 is a cylindrical pattern bar 32, Figs. 1, 6 and 8, preferably of seamless steel tubing, of a diameter equal to the outside diameter of the pipe to be produced. At its lower end, 20 the bar 32 is of reduced diameter, as at 33, to receive a sleeve 34 of an outside diameter equal to the diameter of bar 32, and which is of harder steel to withstand the greater wearing to which the lower portion of the bar is subjected. A plug member 35 is inserted in the top end 36 of the bar to close the bore. At its lower end the bore of the bar is enlarged, as at 37, to provide a shoulder 38, and is internally threaded thereabove, as at 39, to receive a plug member 40 which seats against the shoulder 38 and has an upward extending pin 41 which is threaded for engagement with threads 39 to tightly seat member 40 against shoulder 38. Depending from member 40 concentric with bar 32, is a truncated, conical, centering pin 42 which fits in the bushing bore 22 and which provides a surrounding shoulder 42' which seats on the bottom plate 15. At the upper ends of the bars 32 is a cross-head or supporting member 43 having apertures 44 concentric with the chambers 4 and into which the bars 32 tightly fit. Each of the bars 32 is held in its aperture 44 by a pin 45 passed throughout the cross-head 43 and alined holes 46 in the bars. Depending from the cross-head 43 are centering or positioning pins 47 having a sliding fit in the guide apertures 11 and 24', such that when the pins 47 are in the apertures 11 and 24', the stripper plate 23 will be properly positioned on the flask body and the upper ends of the bars 32 will be held rigidly concentric with their respective chambers 4. The pins 47 are preferably secured to the cross-head 43 by locking pins 48 passed through the cross-head and pins 47. At each end the cross-head is vertically slotted, as at 49, to provide bearing arms 50 through which, adjacent the bottom of the cross-head, are alined apertures 51 to receive a bearing or pivot pin 51.

Pivoted on pins 51 are latch members 52 having hand grips 52'. The members 52 have stops 53 to engage the base of the slots 49 to limit swing of the lower ends of the latch members 52 toward the centering pins

47. Resilient members 54 act on the latch members 52 to normally urge the stops 53 into engagement with the cross-head. Each of the members 54 preferably comprises a coil spring which seats at one end in a socket 55 at the upper end of the base of the slot 49, and which bears at its opposite end against the latch member 52 above pivot pin 51. Each member 52 has an inwardly extending latch tooth 56 which is beveled on its under side, as at 57. The latch members 52 are positioned above the ends of the stripper plate 23 so that they will be guided by the beveled edges 57 to pass through the rectangular openings 58 formed by the hand grips 30 when the plate is raised. As the plate is moved above the level of the teeth 56, the teeth 56 will be moved to supporting position, Fig. 6, beneath the plate 23 by the springs 54 to hold the plate in raised position. On the cross-head 43 between the pins 47 and the latch members 52, are supporting members 59, preferably U-members, secured thereto by studs 60, or the like, threaded into the cross-head. Each of the members 59 has a forwardly projecting, substantially horizontal lug 61 provided with a vertical aperture 62. Carried by the members 59 is a lifter mechanism 63, comprising arm members 64 which depend from the lugs 61, and preferably have hook ends 65 which fit in the apertures 62 to removably support the mechanism from the cross-head. The arm members 64 are preferably rigidly tied together by a rod or bar 66, and each of the members 64 is bifurcated at its free lower end, as at 67, to provide a yoke. Journaled or fulcrumed between the yoke arms of each member 64 on a pin 68 passed therethrough, is a lever member 69 which is bent to provide a bearing part having an arcuate surface, as at 70, to engage the underside of the stripper plate 23 just outside of the sides of the flask body 1. The cross-head 43 is preferably provided with shackles 71 for a hoisting chain, or the like, 72, by which the cross-head and pattern bars 32 may be lowered into position or withdrawn from the chambers 4.

The operation of forming a mold with my improved apparatus, is as follows: The flask body 1 is lifted by a chain hoist or other means engaging the hooks 10, and is placed thereby on the bottom board 15 on the jolt machine platform 16 with the pins 17 passing through apertures 12 to center the body chambers 4 with respect to the bushings 21. The wedges 19 are then driven into the slots 18 to clamp the body 1 in position. The stripper plate 23 is placed on the top flange 5 by means of the hand-grips 30, with apertures 24' and 11 alined, and with the sleeves 26 depending into the chamber enlargements 13. The pattern bars 32 carried by the cross-head 43 are then lowered by a hoist or other means engaging chain 72 through the guide

sleeves 26 of the stripper plate 23 and into the chambers 4. As the centering pins 47 approach the alined apertures 11 and 24', the pins are manually directed into the apertures 24', which will substantially aline the pins 42 with the bushing bores 20. When the pattern bars 32 have been lowered by the cross-head 43 to the position shown in Fig. 1, with the shoulders 42' flush with the plane of the top face of the bottom plate 15, the bars 32 are in operative mold-forming position. However, to insure that the bars 32 are properly seated, the jolt machine is worked a few times. The hooks 65 of the lifter mechanism 63 are placed in the lug apertures 62 with the bearing parts 70 of the lever members 69 positioned beneath the ends of the stripper plate 23, Figs. 2 and 3. The lever members 69 are then pulled downward about their fulcrums 68, i. e., in a clockwise direction of Fig. 2, which will lift the plate 23, sliding it upward on the bars 32 and pins 47 until the latch members 52 pass through the hand-grip openings 58, and the teeth 56 are snapped under the ends of the plate 23 by the springs 54. The lifter mechanism 63 is then unhooked from the cross-head lugs 61, leaving the plate 23 maintained in raised position by the latch members 52. Molding material or sand is shoveled, or otherwise fed into the annular spaces 73 between the walls of the chambers 4 and the bars 32. During this filling of the spaces 73 the jolt machine is operated to pack or ram the sand until the spaces 73 are entirely filled with tightly packed sand and then the jolt machine is stopped. The stripper plate 23 is released from raised position, Fig. 6, by moving the hand-grips 52' of the latch members 52 toward each other against springs 54. The weight of the plate 23 will cause it to slide down on the bars 32 and pins 47 until the sleeves 26 rest on the sand in spaces 73. The jolt machine is again operated to pack or ram the sand at the top of the mold by means of the superposed weight of plate 23 and until the plate takes the position of Fig. 1, with feet 24 resting on the body 1. The plate sleeves 26 also serve, during this last jolting of the body 1, to form the end of the mold print, as indicated at 74 of Fig. 10. The pattern bars 32 are now "drawn" by means of the hoist connected to chain 72. When the patterns have been lifted clear of the flask body 1, the stripper plate 23 is lifted off by an operator and the top end of the mold is cleaned, preferably by a stream of air under pressure. This completes the formation of the hollow cylindrical sand molds, designated 75, Fig. 10, in the flask body 1. The body 1 is then placed on a bottom plate 76 which is substantially similar to plate 15 and is clamped thereto in the same manner as it is clamped to plate 15. The plate 76, however, is provided with cylindrical recesses 77 concentric with bushings 20 and of diameters substantially equal to that of chambers 4. The recesses are filled with molding sand, as at 78, and the sand mold 75 and ring 78 are then hardened, as by baking in an oven or the like. After the mold has been hardened, cores 79, preferably of baked core sand supported on vented core arbors 80, are placed in the chambers 4. The arbors 80 project above and below the cores 79, and at their lower ends converge downward to fit in the bushings 20, which centers the lower ends of the cores. At their upper ends the arbors 80 are removably secured in any suitable manner in an arbor carrier 81, from the underside of which depend pins 82 having a sliding fit in guide apertures 11, and by which the upper ends of the cores 79 are centered. Eyelets or rings 83 may be provided for attaching a hoist to the carrier 81 so that the cores may be simultaneously lowered into the chambers 4. Seated on the print end 74 is the usual pouring ring or cup 84. The mold is now ready for pouring, and the molten metal will fill the annular space 85 to form a hollow tube or pipe.

What I claim and desire to secure by Letters Patent of the United States is:

1. In a molding apparatus, a pattern bar adapted to be positioned in a casting chamber of a flask body, and a stripper plate slideable on said bar, a supporting member secured to and extending transversely of said bar, said plate and said member having co-operable automatically acting means to hold said plate raised from the flask body.
2. In a molding apparatus, a pattern bar adapted to be positioned in a casting chamber of a flask body, a stripper plate slideable on said bar, and resilient catch means carried by said bar, said catch means being operable to engage said plate to hold said plate raised from the flask body.
3. In a molding apparatus, a pattern bar adapted to be positioned in a casting chamber of a flask body, a stripper plate slideable on said bar, a supporting member secured to and extending transversely of said bar, said plate and said member having co-operable means automatically acting to hold said plate raised from the flask body, and means depending from said plate to form the end of the mold print.
4. In a molding apparatus, a pattern bar adapted to be positioned in a casting chamber of a flask body, a stripper plate slideable on said bar, and lifter mechanism supported by said bar and operable to engage said plate to slide said plate upward on said bar to a position above the flask body.
5. In a molding apparatus, a supporting member, a plurality of pattern bars depending from said member, said bars being rigid with said member and adapted to be positioned in the casting chambers of a flask body, and means carried by said member and

acting automatically to support a stripper plate in raised position above the flask body upon engagement of said plate and said means.

- 5 6. An apparatus for forming a pipe mold, comprising a flask body having longitudinal casting chambers, a pattern bar in each of said chambers and forming annular spaces in said chambers to receive mold forming material; means for centering one end of each of said bars in said chambers, the other ends of said bars projecting outside the other ends of said chambers, means supporting said projecting ends to hold said bars in spaced relation, and by which said bars may be inserted in and withdrawn from said chambers, a stripper plate having apertures slidably receiving said projecting ends, said plate being located between said supporting means and the adjacent end of said flask body, and lever means cooperable with said plate to lift said plate on said bars toward said supporting means.

In testimony whereof I have hereunto signed my name.

MALCOLM KENNETH DOUGLAS.
